UNITED STATES PATENT OFFICE.

ANTONIO J. CANOVA, OF JACKSONVILLE, FLORIDA.

GAEOUS-FUEL MIXER.

1,265,047.

Specification of Letters Patent. Patented May 7, 1918.

Application filed December 1, 1916. Serial No. 134,489.

To all whom it may concern:

Be it known that I, ANTONIO J. CANOVA, a citizen of the United States, residing at Jacksonville, in the county of Duval and State of Florida, have invented certain new and useful Improvements in Gaseous-Fuel Mixers, of which the following is a specification.

This invention has relation to fuel vaporizing devices and the nature and objects thereof will be readily apparent to those skilled in the art to which it appertains in the light of the following explanation of the accompanying drawings illustrating what I now believe to be the preferred embodiment, or mechanical expression, of my invention from among other forms and arrangements within the spirit thereof or the scope of the appended claims.

However, an object of the invention is to provide a device adapted for interposition between the carbureter and intake manifold of an internal combustion engine whereby, kerosene oil may be employed as fuel and fed to the carbureter to be vaporized thereby to the extent to which the carbureter is capable of vaporizing this type of fuel, and whereby the vaporized oil may, upon passing through the device be subjected to further treatment to homogenize the vapor permitting the product to be ignited in the cylinders of the engine with the production of less carbon or other undue waste products.

Another object of the invention is to provide a device having the above named characteristics and embodying means whereby the degree of homogenization of the fuel may be varied and the combustible mixture enriched or diluted at the will of the operator.

In addition to the foregoing my invention comprehends improvements in the details of construction and arrangement of parts to be hereinafter more fully described and particularly pointed out in the appended claims.

In the accompanying drawings in which similar and corresponding parts are designated by the same characters of reference throughout the several views in which they appear:

Figure 1, is a view in side elevation diagrammatically illustrating an internal com-

bustion engine and the application of my invention thereto.

Fig. 2, is an enlarged vertical section taken through a gaseous fuel mixing device constructed after the manner of my invention.

Figs. 3 and 4, are transverse sectional views taken on the lines 3—3 and 4—4 respectively of the preceding figure, and

Fig. 5, is a view in vertical section of a modified form of construction.

With reference to the drawings 10 indicates generally the cylinders of a conventional type of internal combustion engine for motor vehicles, motor boats, or the like, 11 indicates the carbureter and 12 the intake manifold.

Interposed between the intake manifold and the carbureter, and at the point of connection thereof, which connection is shown disestablished for the purposes of my invention is a casing of my device indicated at 13. This casing is in the nature of a tube, open at either end and externally threaded at said ends for engagement in the outlet of the carbureter and with the intake of the manifold. This latter connection is established through the medium of a right and left union indicated at 14.

With reference to Fig. 2 of the drawings wherein the construction is set forth in detail 15 indicates a ring or annular member, of which three are provided in the present instance and are disposed transversely within the casing 13 in spaced relation, and connected through the agency of connecting strips 16 which extend longitudinally of the casing. Extending longitudinally and centrally through the casing is a rod 17 which extends beyond the extreme outer rings 15 and is supported at said ends within supporting bearings 18 secured to transversely and diametrically extending metallic strips 19 which are formed with bent terminals 20 whereby said terminals may be secured, through the medium of screws or other fastenings to the interior surface of the casing.

Each of said rings 15 is designed to support one or more layers of wire fabric or some such foraminous material indicated at 22, which are stretched across the rings to entirely fill the space inclosed thereby. Collars 23 are formed upon the central rod 17 at points where said rod passes through

the wire fabric and to which collars the fabric may be secured thereby forming a rigid structure, the rings, connecting members, etc., being removable from the casing 5 when the fastenings 21 are withdrawn.

The elements 22 are preferably of wire fabric of fine mesh as the successful operation of this device depends upon the extent 10 to which the current of vaporized fuel is divided and the constituent fuel particles thereof further divided and sub-divided to cause the vapor to approach a uniform consistency. To this end a plurality of layers of wire mesh are disposed in contact in each 15 ring with the meshes of each layer in overlapping relation so as to provide a greater obstruction to the passage of vapor therethrough, or in other words to provide a finely porous material. If a wire fabric of 20 relatively or extremely fine mesh is employed, only a single thickness for each ring is necessary, but I have found in practice that the provision of a plurality of layers for reasons given above is productive of the 25 best results.

Between adjacent rings 15 I further provide similar rings or annular members 24 which are however provided at diametrically 30 opposite points with outwardly extending trunnions 25 which pass through openings in the walls of the casing whereby the rings may be oscillated to a certain extent. The trunnions are threaded and thumb nuts 26 are applied thereto whereby the rings may 35 be retained in a position to which they are adjusted. In a manner similar to the rings 15, the rings 24 are provided with one or more thicknesses of wire fabric 27 of a degree of fineness corresponding substantially 40 to that of the foraminous elements 22 and are perforated centrally to receive the rod 17.

When starting an internal combustion engine embodying my mixing device it may be necessary to employ gasoline initially or 45 other volatile combustible, but after the engine has been running for a short time and its cylinders have become heated, the carburetor may be supplied with kerosene and the engine will operate successfully with this 50 fuel alone. By suitably disposing the rings 27, which are in the nature of porous butterfly valves, the currents of fuel passing through the device are partly deflected upon 55 contacting with the valves and partly passed through the valves thus permitting and insuring a greater degree of mixture without interrupting the velocity of the vapor currents passing through the device to any considerable extent. The particles of kerosene 60 which form the vapor as it leaves the carburetor, are broken up into finer particles upon passing through the foraminous element and as a result a mixture passes into the manifold which mixture is of a uniform 65 consistency. I have found in practice that

if kerosene oil is used as a fuel for internal combustion engines in connection with a device constructed after the manner of my invention, no great amount of carbonization will take place within the cylinders and the 70 power obtained through the use of this fuel compares favorably with that of gasoline.

In Fig. 5 of the drawings a modified form of my invention is set forth wherein the casing 13 is provided with a plurality of spaced 75 rings 28, all rigidly held in spaced relation through the medium of the connecting strips 16 and a central rod 17. Each of the rings 28 is provided with one or more layers of wire fabric 29 in a manner set forth in connection 80 with the form of my invention first described, and the manner of operation of this form is practically identical with the operation of the other form; the difference resides merely in the omission of the movable valve like elements and a thorough intermixture of kerosene vapor is obtainable 85 by its use.

Thus it will be seen that I have provided a device which is extremely valuable in that 90 it promotes a considerable saving and economy in the use of fuel for internal combustion engines. The device is moreover extremely simple in construction thereby simplifying the operation thereof not to mention the reduced cost of manufacture. 95

While I have illustrated and described my invention with some degree of particularity I realize that in practice various alterations 100 thereover may be made, and I therefore desire to reserve the right and privilege of changing the form of the details of construction or otherwise altering the arrangement of the correlated parts without departing from the spirit of the invention or the scope 105 of the appended claims.

Having thus described my invention what I claim as new and desire to secure by Letters Patent is:

1. In a gaseous fuel mixing device, a casing, 110 a plurality of transversely extending mixing elements mounted therein in spaced relation, each element comprising a plurality of closely spaced layers of foraminous material, and a mixing element of similar 115 construction mounted for oscillation between adjacent stationary elements.

2. In a gaseous fuel mixing device, a casing, 120 a plurality of stationary transversely extending mixing elements mounted therein in spaced relation, mixing elements mounted for oscillation within the casing between adjacent stationary elements, and means operable from without the casing for adjusting said movable elements, said elements comprising a plurality of closely spaced layers of fine mesh wire fabric. 125

3. In a gaseous fuel mixing device, a tubular casing open at either end, a plurality of transversely extending annular members 130

mounted therein in spaced relation, strips connecting said rings, a rod extending longitudinally and centrally of the casing and passing through the rings, means supporting 5 the ends of the rods upon the casing, and a plurality of closely spaced layers of fine mesh wire fabric stretched across each of said annular members.

4. In a gaseous fuel mixing device, a tubular casing open at either end, a plurality of stationary annular members disposed transversely and in spaced relation within the casing, strips connecting said annular members a rod extending longitudinally and centrally of the casing and through the rings, 10 diametrically extending members supporting the ends of the rods upon the casing, a mov-

able annular member between each adjacent aforesaid stationary annular members, trunnions provided upon said movable annular members, said casing having openings to receive the trunnions whereby to support said annular members for oscillation, means engaging the trunnions to retain the annular members against displacement subsequent to 15 adjustment, and a plurality of layers of fine mesh wire fabric inclosed within each of said stationary and movable annular members.

In testimony whereof I affix my signature in presence of two witnesses.

ANTONIO J. CANOVA.
